CONTROLLED FLUID DISPENSING
CONTAINER

Halcolm D. Rives, Los Angeles, Calif., assignor to
Swingspout Measure Company, Los Angeles,
Calif., a corporation of California

Application April 20, 1951, Serial No. 222,101

3 Claims. (Cl. 222—471)

1

This invention is concerned with a controlled fluid dispensing container and it is a general object of the invention to provide an effective, dependable, easily operated device that is inexpensive of manufacture.

Various fluids, and particularly motor oils, are handled or dispensed in containers of particular sizes or capacities and it is common to provide such containers with flexible or shiftable spouts for conducting fluid to points where it is required to be used or deposited. It has long been recognized as desirable or advantageous to provide a container or dispensing device of the character mentioned with a control to govern flow from the body of the container to the spout, and devices or mechanisms that have been proposed and, in some cases, used for this purpose have, for the most part, been rather expensive and tend to be complicated in construction.

It is a general object of this invention to provide a container or fluid dispensing device of the general character referred to having a control or valve governing flow from the body of the container to the delivery spout, the valve being under control of a manually operated means by which it can be opened to any degree and by a manually released gripping means which serves to catch and hold it in any position to which it is moved and which is readily releasable by simple manual operation.

Another object of this invention is to provide a device or structure of the general character referred to in which the body of the container is equipped with an inwardly projecting lip crowned in form, as is common in devices of this general character, which device has the parts so arranged and related that the entire gripping means, save the manually accessible portion, is within the cavity defined by the lip.

It is a further object of this invention to provide a container of the general character referred to wherein the gripping means which serves to grip and hold the valve operating mechanism is formed by and involves a single part which is of very simple, inexpensive form, construction and mounting.

In the construction of the present invention the container has a body that is cylindrical in form. A bottom is provided in the body at the lower portion thereof, there being a skirt portion of the body depending below the bottom forming a chamber at the lower end or bottom of the structure. A lip is provided at the upper end of the body and may be of the form and type common to devices of this character, that is, it may be crowned in cross-section or substantially half-round, and may have its outer edge fixed or se-

2

cured to the upper end of the body while its inner edge is inward of the upper end of the body and is in about the same plane as the outer edge. A handle is provided on the body and preferably involves an upper arm projecting outwardly or away from the body at the upper end portion thereof, and a lower arm projecting outwardly from the body at the lower end portion thereof, for instance, from the skirt. A grip extends between the arms and, in practice, the arms and grip are formed of a single continuous element, elongate in form and having its ends fixed or secured to the exterior of the body. A discharge means is provided and, in a typical case, involves a section located in the chamber at the lower end of the body and in communication with the interior or fluid carrying compartment of the body through an opening in the bottom. Another section of the discharge means is joined to or extends from the first mentioned section and may be shiftable or flexible in the manner common to devices of this general character. A valve is provided to control flow of fluid from the compartment defined by the body to the discharge means or spout, and a manually actuated operating means is provided for operating the valve. In a preferred arrangement the valve operating means involves a stem with a portion located in the body and a portion accessible at the exterior of the body. The stem may be slidably carried by the lip by a bracket in the body so that the manually engageable portion is above the lip and is accessible to a thumb or finger of a hand engaging the handle. A lever operatively connects the stem and valve and may be pivotally mounted with one arm connected or linked to the lower end of the stem while another arm carries the valve. A suitable means such as a spring normally yieldingly holds the stem in a position where the lever operated by the stem holds the valve closed, thus preventing flow of fluid from the body or compartment to the discharge spout. The invention provides a manually operable releasable gripping means that serves to catch and hold the valve operating means upon its being moved to any degree or extent from the position where the valve is closed. This gripping means is preferably confined to the lip or upper end portion of the structure where the lip is located, and it is characterized by a single element anchored to or mounted on the body or a part thereof, such as the lip, and having a free flexible arm that carries a jaw engaged with the stem of the valve operating means. An actuating element projects from the jaw through an opening in the lip and presents a manually engageable part at the exterior of

the structure in position to be conveniently actuated by the thumb or finger of a hand engaged with the handle. The structure is such that simple manual depression of the actuating element frees the gripping means, allowing the spring of the spring actuating means to immediately return the valve to the closed position and this is regardless of the extent to which the operating means has been previously actuated.

The various objects and features of my invention will be fully understood from the following detailed description of typical preferred forms and applications of my invention, throughout which description reference is made to the accompanying drawings, in which:

Fig. 1 is a side elevation of a structure embodying the present invention, a portion thereof being broken away to show details of the mechanism involved. Fig. 2 is an enlarged view taken substantially as indicated by line 2—2 on Fig. 1. Fig. 3 is an enlarged plan view of a portion of the structure taken as indicated by line 3—3 on Fig. 1. Fig. 4 is a detailed sectional view through the portion of the structure shown in Fig. 3, being a view taken in the direction indicated by line 4—4 on Fig. 3. Fig. 5 is a transverse sectional view taken as indicated by line 5—5 on Fig. 3. Fig. 6 is an enlarged detailed sectional view taken as indicated by line 6—6 on Fig. 5. Fig. 7 is a transverse sectional view taken as indicated by line 7—7 on Fig. 3. Fig. 8 is a sectional view taken at the valve that controls flow from the container to the spout and Fig. 9 is a view illustrating a modified form of hook construction suitable for retaining the spout in a predetermined position when the structure is not in use.

The structure embodying or to which the present invention is applied involves a container A formed by a body 10 having a bottom 11 and preferably provided with a lip 12 at its upper end. The container is provided with a handle B and a discharge means or spout mechanism C is provided to handle fluid from the container. A valve D is provided to control flow from the container to the spout and an operating means E is provided for actuating the valve. A manually operable releasable gripping means G is provided to catch and hold the means E upon its being actuated to any degree from a position where the valve D is closed and is adapted to be manually operated to free the means E so that it operates the valve to a closed position.

In a typical construction, the body 10 of the container is a vertically disposed cylindrical element and the bottom 11 is fixed in the lower portion of the cylindrical body closing it and establishing a fluid carrying compartment 13. In accordance with typical or conventional construction, the body has a skirt portion 14 depending from or projecting somewhat downwardly below the bottom 11 forming an open chamber 15 at the lower end portion of the structure. The skirt opens downwardly and is provided with a plurality of side openings 16, making it apparent that the chamber 15 exists in the structure below the bead 17 provided around the bottom 14 where the bottom 11 occurs.

At the upper end of the body 10 it has a lip portion or a lip 12 is applied thereto and, in accordance with typical or conventional construction, the lip projects inwardly from the upper end of cylinder body 10 and is crowned or substantially semi-circular in cross-sectional configuration. The outer edge 20 of lip 12 is joined or fixed to the upper end of the cylindrical bot-

tom 10 while the inner edge 21 of the lip is inward of the edge of the body and is in about the same horizontal plane as the outer edge 20. In the case illustrated, a limited flat horizontal flange 22 projects from the inner edge 21 of the lip. The lip construction extends continuously around the upper end of the body or container and it serves to define a cavity 23 that opens downwardly or faces into the compartment 13.

10 The flange lip provided on the upper end of body 10 as hereinabove described and as illustrated throughout the drawings serves as a gauge indicating the extent to which fluid is filled into the container and serves to effectively check or 15 retard spilling of fluid from the container in the course of normal operation of the device.

The handle B is provided at the exterior of the container and a typical handle such as is shown in the drawings involves an upper arm 30 projecting outwardly or away from the body at the upper end portion thereof, a lower arm 31 projecting outwardly from the body at the lower end portion thereof, and a hand grip carried by and extending between the arms. In the case 20 illustrated, the arm 30 is joined to the body at the upper end thereof adjacent the lip 12 and it projects outwardly or away from the body at a point opposite or in substantially horizontal alignment with the lip. The lower arm 31 is 25 joined to or projects from the skirt portion 14 of the body. The portions 30, 31 and 32 of the handle are in the nature of a single elongate member or structure, the ends of which are joined to the body as at points 33 and 34.

30 The discharge means C provided for handling fluid from the container may, insofar as the present invention is concerned, be varied widely in form and construction. In the particular case illustrated, the means C involves two sections, an inner section 35 that is located in the chamber 15 and an outer section 36 which is joined to or carried by the section 35 which occurs at the exterior of the structure and is in the form of a duct of substantial length. The inner section 35, in the case illustrated, is in the form of a rigid elbow-like fitting having one end open to or in communication with the compartment 13 of the container through an opening 38 provided in the bottom 11 of the container. The other end of section 35 projects through or is accessible at an opening 16a provided in the skirt portion of the body 10. The section 36 of the discharge means is shiftable or flexible and in the particular case illustrated it is an elongate flexible tube having one end fixed to and in communication with the fitting 35 while its other end carries a suitable nozzle 39. The section 36 which is, in effect, a spout is of substantial length and in the drawings I have illustrated a retaining means 40 in the form of a hook 40 serving to releasably hold the section 36 in an up or substantially vertical position when the structure is not in use. In the form of the invention shown in Figs. 1 and 2 of the drawings, the hook 40 is of simple form and includes a shank 41 pivoted to the body at 42 and has a head 43 shaped to be hooked around the spout section 36.

In Fig. 9, I illustrate a form of hook 40a where- 70 in there are two spaced parallel arms 41a pivoted to the body at 42a and having opposed hook parts 43a and outer ends between which the spout section 36 is received.

The valve operating means E may vary widely 75 in form and construction. In the drawings, I

have illustrated a simple, effective means E characterized by a reciprocating stem 50, a pivoted lever 51 and an operating spring 52. In the case illustrated, the stem 50 is a simple, elongate member with a portion 54 located in the compartment 13 of the container and with a portion 55 accessible or located at the exterior of the container. The preferred arrangement provides for mounting of the stem by means of the lip 12 and a bracket 56 provided in the body 10. When this construction is employed, an opening 57 is provided in the lip 12 and slidably passes the stem 50 and a bracket 56 is fixed to the inner wall of body 10 and projects inwardly therefrom below the opening 57 and has an opening 58 slidably passing the stem 50. In accordance with the invention the stem 50 is rounded as above described so that the portion 55 thereof projects above the container or above the lip 12 of the container in the immediate vicinity of the handle, that is, at a point close to the arm 30 of the handle. By thus locating the stem 50 its exposed portion 55 is readily accessible to a thumb or finger of a hand gripping the handle 13. For purpose of convenience I provide a suitable knob 60 on the upper or terminal end of stem portion 50, as shown throughout the drawings.

The lever 51 is located in the compartment 13 and, in the case illustrated, it is carried by a pivot pin 61 supported by a suitable bracket 62 which projects up from the bottom 11 of the container. The lever 51 has an arm 63 which is linked or connected to the lower end of the stem 50 and it has an arm 64 which carries the valve D. In the particular construction illustrated, the connection provided by the lower end of the stem 50 and the arm 63 allows certain limited movement or flexibility between these parts and is in the form of a lug 70 projecting from the end of arm 63 and engaged in an opening 71 provided in the flattened lower end 12 of the stem. The lever 51 with the arms 63 and 64 is normally substantially horizontal in the lower portion of compartment 13, except for the terminal end portion 74 of the arm 63 which projects downwardly and occurs over or in line with the opening 38 provided in the bottom 11 of the container.

The valve D is carried by the depending or downwardly projecting portion 74 of arm 64 and in the form of construction illustrated it involves a disc-like body 80 of suitable sealing material carried between two rigid discs or plates 81 and 82. The body 80 of the valve projects radially beyond the discs 81 and 82 and is adapted to seat on or have sealing engagement with the bottom 11 where it surrounds the opening 38. The valve parts just described may be mounted on or secured to the lever arm 74 in any suitable manner. In the case illustrated, the valve parts are provided with a central registering slot which receives a tab 85 which projects down from the arm portion 74, the tab being spread at 86 so that the valve parts are maintained on the valve.

The spring 52 is provided to normally yieldingly hold the stem 50 in an up position so that the lever 51 is held in position where the valve D is closed. In the case illustrated, the spring 52 is a helical compression spring carried on the lower portion 54 of the stem between the bracket 56 and a stop 78 provided on the stem.

The manually operated releasable gripping means D, provided by the present invention, serves to catch and hold the valve operating means E, preferably the stem 50 thereof, upon its being moved to any extent from the position

where the valve D is closed. The means G is characterized by an elongate flexible arm 90 having one end fixed or anchored to the container, as, for instance, to the container through suitable means such as fasteners 91. The means G further includes a gripping jaw 92 on or projecting from the other or free end of the flexible arm and an actuating element 93 projects from the jaw and has a portion accessible at the exterior of the container so that it can be readily actuated manually.

The flexible arm, the jaw 92, and the actuating element, except for the portions required at the exterior of the structure, are preferably located entirely within the container and it is preferred that they be located entirely within the downwardly opening cavity 23 provided in or formed by the lip 12 of the container.

The arm 90 is preferably an elongate member of suitable length and as shown in Fig. 2 it is preferably curved or arcuate and of the same curvature as the neck 12, so that it extends around within the cavity 23 with clearance or free of the lip parts. The anchored or fixed end 94 of the arm 90 is preferably rounded or shaped to conform to the inner surface or side of the lip 12 and, in practice, the fastening means 91 employed to anchor or secure the end 94 to the lip may be any suitable means. I have shown screw fasteners serving this purpose. The free or flexible portion of arm 90 extends around and somewhat downward from the anchored end 94 so that the free end 95 of the arm is spaced a considerable distance below the top or crown of the lip.

The jaw 92 may be a flat plate-like portion projecting or continuing from the free end 95 of the arm and it has an opening 97 that passes the stem 50 of the means E. In accordance with the invention, the jaw or plate 92 extends beyond the end of the arm 90 and somewhat upward so that the plane of the jaw is pitched or inclined relative to the longitudinal axis of the stem. The opening 97 in the body that passes the stem is somewhat larger than is required to pass the stem and the size of the opening 97 is related to the pitch or angular disposition of the jaw so that normally diametrically opposite edge portions 98 of the openings 97 engage or grip the stem. The arm 90 and the jaw 92 are shaped and proportioned so that the arm 90 normally yieldingly urges the jaw upwardly or in a manner to cause gripping of the stem by the jaw.

The actuating element 93 of means G is preferably carried by or projects from the jaw, for instance, the upper edge portion of the jaw, and it has a shank portion 100 that projects upwardly through an opening 101 provided in the lip 12. The opening 101 passes the shank 100 with clearance. The portion of the shank projecting above the lip 12 forms a part conveniently accessible from the exterior of the structure so that the actuating element can be engaged and depressed at will. It is preferred, in practice, to provide a suitable knob 102, or the like, on the upper end of the shank 100 and it is preferred to shape or form the knob 102 somewhat differently than knob 60 so that a person can readily determine by feel which knob is engaged.

In accordance with the invention, the jaw 92 and the portion 100 of the element 93 joined to the jaw 92 form, in effect, a continuation or extension of the arm 90 and combine with the arm to form an arcuate or curved unit that extends around within the cavity 23 in a manner clearly illustrated in Fig. 2 of the drawings. In

accordance with the present invention, it is preferred that the jaw 92 and the actuating element 93 be formed of a single body or strip of material so that they form a simple, compact element that is very simple and inexpensive of manufacture, and which is such that it can be incorporated in the construction easily, quickly, and at little cost. Furthermore, it is preferred, in accordance with the present invention, that the shank 100 of element 90 with its knob 102 be formed or related to the shank 50 so that the knob 102 occurs, in effect, adjacent the knob 60 or in the vicinity of the arm 30 of handle B, so that the thumb or finger of a hand engaged with the handle can conveniently reach and operate either of the knobs.

In operating the structure, a suitable fluid, say, for instance, oil, can be filled into the container, and under normal conditions the valve operating means E holds the valve D closed. The container carrying the desired quantity of fluid can be manipulated or handled in any suitable manner, and when it is desired to deliver or deposit the fluid the spout section 36 freed from the hook 40 can be swung or flexed in any suitable manner, for instance, to extend downwardly or in any suitable direction from the container. When desired to discharge the material from the container, the operator depresses the stem 50, as by engaging the knob 60, and, in practice, the stem 50 can be depressed any suitable degree to open the valve D the desired amount. As the stem 50 moves downwardly or is depressed, it slides through the jaw and is caught or held by the jaw so that it cannot move upwardly under the influence of spring 52 after the operator has released downward pressure from the stem. The jaw 92 operated by the arm 90 will maintain its hold or grip upon the stem until the operator desires to release the mechanism so that spring 52 closes the valve D. To effect release of the mechanism and the closing of the valve, the operator depresses shank 100 as by pressing down on knob 102. This moves the jaw downward or changes the angle of the jaw relative to the stem so that the edges 98 gripping the stem release it. When the stem is released the spring 52 acts to immediately operate the stem vertically, with the result that the lever 51 is operated so that the valve D is closed.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A liquid handling device including, a container having a cylindrical body, a bottom at the lower portion of the body and an inwardly projecting lip extending around the upper end of the body, the lip being crowned in cross section and defining an annular downwardly facing cavity, a spout in communication with the body through the bottom and having a section shiftable relative to the container, a handle on the container at the exterior of the body with a portion in the vicinity of the lip, a valve controlling flow from the body to the spout, operating means for the valve including, a lever pivoted in the body and carrying the valve, a stem connected to the lever and projecting upwardly to a point above the lip and in the vicinity of the handle, and a spring normally holding the stem in a

5 raised position with the valve in a closed position, and stem gripping means including, a flexible arm having one end fixed to the container, a jaw carried by the arm and normally held thereby in gripping engagement with the stem, and an actuating part at the exterior of the container and in the vicinity of the handle and depressible to release the grip of the jaw, the arm and jaw forming an elongate curved part confined in said cavity.

2. A liquid handling device including, a container having a cylindrical body, a bottom at the lower portion of the body and an inwardly projecting lip extending around the upper end of the body, the lip being crowned in cross section and defining an annular downwardly facing cavity, a spout in communication with the body through the bottom and having a section shiftable relative to the container, a handle on the container at the exterior of the body with a portion in the vicinity of the lip, a valve controlling flow from the body to the spout, operating means for the valve including, a lever pivoted in the body and carrying the valve, a stem connected to the lever and projecting upwardly to a point above the lip and in the vicinity of the handle, and a spring normally holding the stem in a raised position with the valve in a closed position, and stem gripping means including, an elongate flexible arm having one end fixed to the lip in said cavity, a gripping jaw below the lip on the other end of the arm and having an opening passing the stem and having edges gripping the stem, and a manually operated actuating element projecting from the jaw and to a point above the lip.

3. A liquid handling device including, a container having a cylindrical body, a bottom at the lower portion of the body and an inwardly projecting lip extending around the upper end of the body, the lip being crowned in cross section and defining an annular downwardly facing cavity, a spout in communication with the body through the bottom and having a section shiftable relative to the container, a handle on the container at the exterior of the body with a portion in the vicinity of the lip, a valve controlling flow from the body to the spout, operating means for the valve including, a lever pivoted in the body and carrying the valve, a stem connected to the lever and projecting upwardly to a point above the lip and in the vicinity of the handle, and a spring normally holding the stem in a raised position with the valve in a closed position, and stem gripping means including, an elongate flexible arm having one end fixed to the lip in said cavity, a gripping jaw below the lip on the other end of the arm and having an opening passing the stem and having edges gripping the stem, and a manually operated actuating element projecting from the jaw and to a point above the lip, the lip having spaced openings in the vicinity of the handle and passing the stem and said element.
